(57) **CLAIM**

I claim the ornamental design for a lighting fixture, as shown and described.

DESCRIPTION

FIG. 1 is a bottom perspective view of the lighting fixture of the invention.

FIG. 2 is an elevation view of the lighting fixture of the invention.

FIG. 3 is an elevation view of the lighting fixture of the invention.

FIG. 4 is an elevation view of the lighting fixture of the invention.

FIG. 5 is an elevation view of the lighting fixture of the invention.

FIG. 6 is a top plan view of the lighting fixture of the invention.

FIG. 7 is a top perspective view of the lighting fixture of the invention.

FIG. 8 is a bottom plan view of the lighting fixture of the invention.

FIG. 9 is a bottom perspective view of an alternate embodiment of the lighting fixture of the invention.

FIG. 10 is an elevation view of the lighting fixture of FIG. 9.

FIG. 11 is an elevation view of the lighting fixture of FIG. 9.

FIG. 12 is an elevation view of the lighting fixture of FIG. 9.

FIG. 13 is an elevation view of the lighting fixture of FIG. 9.

FIG. 14 is an elevation view of the lighting fixture of FIG. 9.

FIG. 15 is an elevation view of the lighting fixture of FIG. 9.

FIG. 16 is a top plan view of the lighting fixture of FIG. 9.

FIG. 17 is a top perspective view of the lighting fixture of FIG. 9.

FIG. 18 is a bottom plan view of the lighting fixture of FIG. 9.

FIG. 19 is a bottom perspective view of another alternate embodiment of the lighting fixture of the invention.

FIG. 20 is an elevation view of the lighting fixture of FIG. 19.

FIG. 21 is an elevation view of the lighting fixture of FIG. 19.

FIG. 22 is an elevation view of the lighting fixture of FIG. 19.

FIG. 23 is an elevation view of the lighting fixture of FIG. 19.

FIG. 24 is an elevation view of the lighting fixture of FIG. 19.

FIG. 25 is an elevation view of the lighting fixture of FIG. 19.

FIG. 26 is a top plan view of the lighting fixture of FIG. 19.

FIG. 27 is a top perspective view of the lighting fixture of FIG. 19; and,

FIG. 28 is a bottom plan view of the lighting fixture of FIG. 19.

The broken lines are for illustrative purposes only and form no part of the claimed design.

1 Claim, 28 Drawing Sheets
